Attorney.

UNITED STATES PATENT OFFICE

2,009,083

SOAP DISPENSER

Loui Florence, Peterboro, Ontario, Canada

Application June 11, 1934, Serial No. 730,034

2 Claims. (Cl. 221—106)

The invention appertains to dispensers for powdered or granulated substances, particularly soap, whereby a given quantity of such substance is discharged each time the appliance is operated.

5 In dispensers of this nature it has already been proposed to employ an agitating agent in the receptacle with a view to causing the contents to freely drop into the measuring pockets. The agitating agents proposed are in the nature of rods or bent spring bars adapted to shift or flex laterally of the receptacle in the movement of a pocket away from the discharge opening. In practice it has been ascertained that these rods or bars do not uniformly agitate the contents but 10 have a tendency to pack the contents against the wall of the receptacle toward which they move.

15 A paramount object of the instant invention is the production of an efficient and serviceable dispenser in which the contents are uniformly agitated or joggled throughout the entire mass in the lower part of the receptacle. This distributed joggling ensures a free flow to the pockets of the control member with the result that a full measure is discharged at each operation. Furthermore the discharge passage does not become 20 blocked and the dispenser rendered inoperative.

25 Another object of the invention is to provide a dispenser simple of construction, easy of assembly and inexpensive to manufacture.

30 Referring to the accompanying drawing; Figure 1 is a vertical sectional view of the improved dispenser.

Figure 2 is a fragmentary sectional view thereof taken on the line 2—2.

35 Figure 3 is a cross section taken on line 3—3 of said Figure 1.

In the drawing the reference numeral 5 denotes the receptacle in which the contents are stored, which has the usual fill-cap 6. The receptacle is formed in two main parts, an upper body and a lower member 7 comprising a throat 8 presenting a converging passage 9 leading to a discharge spout 10.

40 The upper wide end of the throat has an annulus 11 in which the lower end of the aforesaid body is fitted and seated by a shoulder 12. The body is secured to the throat by suitable locking means, which by way of illustration may consist of a grub screw 13 engaged in a groove 14 supplied in the ring portion 15 of the body.

45 The lower member 7 has an integral bracket 16 extending from the throat 8 for attachment to a supporting wall.

50 The bottom of the throat merges into a housing 17 containing the control member for dis-

charge of the contents, which member comprises a plug 18 of a cylindrical shape turnably disposed and furnished with a grip portion 19. The grip end of the plug is shouldered at 20, while the other end has a compression spring 21 shouldered in a counterbore in the housing and seated against a disc 22 on the reduced end 23 of the plug. A split locking ring 24 forms a shoulder for the disc.

5 By this construction it will be apparent that the control member is securely held against displacement, but is free to be turned by the grip portion 19. The cylindrical plug has a pair of diametrically opposite pockets 25 which are brought into register with the discharge spout 10 by manually turning the grip portion 19. When the lower pocket is in register with the spout the upper pocket is in position for receiving a supply 10 of the contents which is dispensed by a half turn 15 of the control member.

20 The agitating agent comprises a volute spring 26 conforming substantially to the converging walls of the passage 9 and having its successive coils of a slightly less diameter than the passage so as to be free to operate therein. The bottom 25 coil is integral with a curved element in the shape of a ring 26' that rests on the control member 18 and engages in either of the pockets whichever is uppermost. The top coil is engaged by lugs 27 inwardly protruding from the ring portion 15 of 30 the body. These lugs hold the spring under slight tension in order that as the ring rides over the girth of the plug it will be forced into a pocket approaching the passage. The dilation of the coils urges the contents downwardly into this 35 pocket to fill it.

35 By fashioning the receptacle in two parts and forming the lugs on the upper part the spring is held in place when the two parts are assembled.

40 What I claim is:—

1. In combination, in a dispenser of the class described, a receptacle formed in two parts consisting of a hollow body having an open lower end, and a throat member having an open top portion in which the lower end of the body is seated, said 45 throat member having a downward passage terminating in an egress, a discharge spout in alignment with said egress, a rotatable control member interposed between the egress and the spout and supplied with a pocket for registering therewith, a helical coil spring coaxially lodged in the passage and consisting of a series of turns of a slightly less diameter than the passage, said spring extending substantially the full length of 50 the passage and having its coils horizontally dis- 55

posed, projections on the aforesaid lower end of the body forming a shoulder for the upper end of the spring, and means contacting with the control member and associated with the spring to 5 agitate its coils so as to uniformly disturb the contents of the passage.

2. In combination in a dispenser of the class described, a receptacle having a downward passage terminating in an egress, a discharge spout 10 in alignment with said egress, a rotatable control member interposed between the egress and the spout and supplied with a pocket for registering

therewith, a helical coil spring coaxially lodged in the passage and consisting of a series of turns of a slightly less diameter than the passage, said spring extending substantially the full length of the passage and having its coils horizontally disposed, means providing a shoulder for the upper end of the spring, and a ring integrally constructed with the lower end of the spring for riding on the control member and engaging in the pocket thereof.

LOUI FLORENCE.
